EMULSION TREATING METHODS AND
MEANSClarence O. Glasgow, Tulsa, Okla., assignor to
National Tank Company, Tulsa, Okla., a corporation of Nevada

Application May 1, 1948, Serial No. 24,651

12 Claims. (Cl. 183—2.7)

1

This invention relates to new and useful improvements in emulsion treating methods and means.

It has been found difficult in many instances to treat effectively certain types of crude petroleums, especially those which are relatively heavy and viscous and which in addition may contain considerable quantities of gas. Such heavy petroleums are not readily handled since they resist flow and agitation whereby the mixing of emulsion treating chemicals therein is impaired, and the washing steps important to adequate emulsion treating are rendered quite difficult to effect to the desired degree.

The present invention overcomes these problems to a large extent by heating the heavy emulsion stream as a first step so that the viscosity of the petroleum is lowered before any further treatment is applied. This same initial heating step also frees large portions of contained gas from the emulsion stream, both by the raising of the stream temperature and by the reduction of its viscosity. In this manner, this novel treating method and means achieves, with a minimum of equipment, efficient and thoroughly satisfactory treating of heavy petroleum emulsions. In previous methods, excessively expensive and voluminous equipment has been required for the treating of these heavy oils. While slightly greater percentages of gas are driven off in the carrying out of this method and in the initial steps thereof, it is usually the case that such quantities of gas will eventually be required in any event to obtain the degree of heating necessary for proper treating of the emulsion. Thus, the invention attains an additional beneficial result in providing gas in quantities sufficient to meet its own heating requirements. This feature is especially important in handling crude petroleums having low gas-oil ratios. It has often been necessary in the past to purchase gas from outside sources for fuel purposes in treating such a crude petroleum. This method is self-sustaining in that it provides adequate quantities of gas for its own need, it being kept in mind that any excessive quantities of gas so produced are readily marketable and do not represent an economic or conservation loss.

Another object and beneficial result of this invention is the provision of an emulsion treating method and means wherein the emulsion stream is thoroughly agitated following the heating step so that emulsion treating chemicals which may have been added are thoroughly

2

mixed and incorporated into the emulsion whereby they may exert their maximum beneficial effect.

Yet another object of the invention is to provide an improved emulsion treating means of the character described in which the emulsion undergoes an initial washing step immediately following the primary heating, both in the heating chamber and in the conduit leading to the turbulence chamber, whereby a partial initial separation of the emulsified components takes place along with the considerable degree of degasification.

A further object of the invention is to provide a method and means of the character described in which the heated emulsion stream passing to the turbulence chamber acts as a heating means in passing upwardly through the washing chamber of the treater whereby a considerable degree of heat exchange and maintenance of temperature within the washing chamber is realized.

A construction designed to carry out the invention will be hereinafter described together with other features of the invention.

The invention will be more readily understood from a reading of the following specification and by reference to the accompanying drawings, wherein examples of the invention are shown, and wherein:

Fig. 1 is a vertical, sectional view of an emulsion treater constructed in accordance with this invention and adapted to carry out this method,

Fig. 2 is a horizontal, cross-sectional view taken on the line 2—2 of Fig. 1,

Fig. 3 is a horizontal, cross-sectional view taken on the line 3—3 of Fig. 1,

Fig. 4 is a vertical, sectional view of a modified form of the emulsion treater, also adapted to carry out this method,

Fig. 5 is a horizontal, cross-sectional view taken on the line 5—5 of Fig. 4, and

Fig. 6 is a horizontal, cross-sectional view taken on the line 6—6 of Fig. 4.

In the drawings, the numeral 10 designates an upright emulsion treater tank having a domed upper end 11 and a dished bottom 12. The usual tank support 13 is provided at the lower end of the tank 10, and a clean out drain 14 leads from the central portion of the dished bottom 12.

In the lower portion of the tank immediately above the bottom 12, a heating chamber A is provided by the positioning of a domed partition 15 spaced a short distance above the bottom 12.

The usual return bend fire tube 16 is provided

within the chamber A, but it is to be pointed out that any other suitable or desirable heating means such as steam coils, indirect heaters, electrical heaters, and the like, may be employed in place of the fire tube 16. An emulsion stream inlet pipe 17 extends radially into the chamber A near the lower portion thereof and has its open inner end terminating in a suitable spreader device 18 mounted immediately below the heater tube or fire tube 16. The heating chamber A is normally full of hot water which has a greater average density than the incoming emulsion stream whereby the latter, upon admission to the spreader 18, is caused to flow upwardly around the heater tube 16 in the usual fashion. The emulsion stream is thus heated to the desired degree both by contact with the heater tube and by passage through the heated body of water present in the chamber A. The heater tube functions to heat the emulsion stream and also to maintain said body of water at the desired temperature, the latter taking place by the thermo-syphonic and convection currents which will naturally arise within the chamber A. In this manner, the washing of the influent emulsion stream is begun even while the initial heating of said stream is being effected, and it may be stated that the breaking of the emulsion begins at this point since a part of the looser portions of the emulsion will begin to separate in this section of the treater and at this step in the method. Of course, any desired means such as thermostatic controls (not shown) may be employed to regulate the degree of heating obtained from the fire tube 16.

A turbulence chamber B is provided in the upper end of the tank 10 beneath the head 11 by the provision of a dished partition 19 spaced a short distance below said head. The provision of the head 11 also forms a large central washing chamber C between said partition and the lower partition 15. A relatively large flume 20 extends vertically through the central portion of the tank 10 so as to be substantially axially disposed with respect thereto, the flume extending from the uppermost portion of the chamber A through the partitions 15 and 19 to a point within the upper portion of the chamber B spaced a short distance below the top or head 11 of the tank. Above the upper end of the flume 20, a gas scrubbing chamber is provided by means of a cylindrical housing 21 secured to the underside of the head 11. The housing 21 is formed with a downwardly directed conical bottom 22 from which depends a circular, horizontal, deflector plate 23 immediately overlying the open upper end of the flume 20. The plate 23 is formed with a depending marginal flange 24 so that the emulsion stream passing upwardly through the flume 20 is deflected downwardly and radially outwardly from the upper end of said flume. A pair of circular, disc-like baffles 25 are mounted upon the exterior of the flume near its upper end and within the chamber B, said baffles being welded or otherwise suitably secured to the flume and extending radially outwardly therefrom, but terminating short of the side wall of the chamber B. A circular plate baffle 26 is disposed between the pair of baffles 25, the baffle 26 being in the form of a disc-like element secured in any suitable fashion to the side wall of the chamber B and extending radially inwardly in a horizontal plane between the baffles 25 and toward the upper portion of the flume 20. An enlarged circular opening 27 is provided at the central portion of the plate 26, said opening being considerably greater

in diameter than the flume 20 so that an annulus 28 is provided between the wall of the opening 27 and the outer periphery of said flume. A spider 29 bridges the space between the outer wall of the flume and the body of the plate 26 so as to center and support the upper end of the flume concentrically with respect to the opening 27.

With this structure, the emulsion stream directed downwardly and outwardly by the plate 23 and the skirt 24, is caused to flow over the upper surface of the upper plate 25 in a radially outward direction, said stream falling from the outer edge of the plate 25 onto the plate 26 on which it must pass radially inward to the opening 27. The emulsion stream then flows downwardly through the annulus 28, striking the lower baffle 25 and again flowing outwardly to pass over the outer edge of the latter plate and onto the partition 19 or into the lower portion of the chamber B. During this circuitous flow path, the emulsion stream is obviously subjected to considerable turbulence so that emulsion treating chemicals which have previously been added, are thoroughly admixed and commingled with said stream so as to exert their maximum efficacy in breaking the emulsion being treated. At the same time, the turbulence and agitation achieved, in view of the heated condition of the emulsion stream, release substantially all desirable quantities of gas therefrom whereby the residual emulsion is much more easily handled and treated.

The released gas passes upwardly in the chamber B and enters into the housing 21 through suitable diverter baffles 30. In the housing 21, the gas is thoroughly scrubbed so as to move entrained liquids therefrom, and passes outwardly through a gas vent pipe 31 connected through the head 11 into the upper end of said housing. The removed liquids flow from the housing through a drain tube 32 into the lower portion of the chamber B and are thereby conserved and returned to the emulsion stream.

It is to be noted that in addition to the preliminary washing action effected upon the incoming emulsion stream in the heater chamber A, the stream will also be subjected to a washing action in the relatively large diameter flume 20. A considerable portion of this flume, and especially the lower portion thereof, will be filled at all times with a liquid consisting largely of heated water, so that the emulsion stream, in passing upwardly through the flume, is washed and treated to a considerable extent whereby additional separation of the emulsified components takes place. At the same time, the hot emulsion stream flowing upwardly from the heater tube 16 will maintain the interior of the flume 20 at a considerably elevated temperature whereby the flume functions to some extent as a heat exchanger and increases the temperature of the contents of the washing chamber C which surrounds said flume on all sides. Any heat radiated or conducted from the flume 20 is thus utilized in an advantageous manner and is not lost by being dissipated to the atmosphere.

The washing actions occurring in the heater chamber A and in the flume 20, along with the thorough admixture of any treating chemicals within the chamber B and the degasification in the latter chamber, place the emulsion stream in a condition wherein sizable quantities of the emulsified components have separated, or will easily separate if allowed to settle for a short period. Such a settling period occurs in the

lower portion of the turbulence chamber B as the emulsion stream accumulates upon the upper side of the partition 19. Being placed in a condition in which further breaking of the emulsion and stratification of the components thereof is encouraged, a further sizable separation will take place at this point and a considerable degree of the desired emulsion treating will have been completed before the stream passes into the washing chamber C. In such passage, the components are not again emulsified and seek their respective levels almost immediately after introduction into said washing chamber.

The emulsion stream is conducted downwardly from the chamber B by a smaller vertical flume 33 connected into one side of the partition 19 and extending downwardly to a point within the chamber C spaced a short distance above the upper surface of the lower partition 15. The lower portion of the washing chamber is normally occupied by a body of hot water, usually salt, and the partially treated emulsion stream is thus directed into the lower portion of said body of water. Being of lesser density than the water, the emulsion stream flows upwardly therethrough and is washed in such passage so as to complete the emulsion treating operation resulting in the separation of the components of the emulsion and their stratification into respective levels. To supplement the treating and washing action achieved in the chamber C, a hay section 34 is provided in the central portion of said chamber. The hay section includes a body of excelsior, straw, or other similar materials, 35 confined between an upper partition 36 and a lower partition 37. The upper partition 36 is spaced some distance below the partition 19, while the lower partition 37 is spaced a similar distance above the lower partition 15. It will be noted that the down flume 33 extends below the lower partition 37 and is disposed in the left-hand portion of the tank 10 as viewed in Fig. 1. To insure a longer and more circuitous flow of the emulsion stream through the washing water, the left-hand portion of the partition 37 is imperforate, while the right-hand portion is provided with a plurality of small openings 38 through which the emulsion stream may flow. The stream is thus caused to flow laterally across the chamber C beneath the partition 37 before being allowed to flow upwardly in many small streams into the hay section 34. For the same purposes, the right-hand portion of the upper partition or plate 36 is free of openings, and a plurality of small openings 39 are cut in the left-hand portion of the latter plate. With this structure, the emulsion stream, in addition to being forced to flow through the height or thickness of the hay section, is also required to flow transversely thereof across the body of the washing chamber C. In this manner, the washing action is increased and more efficient and complete emulsion breaking is achieved. A water drain pipe 37 extends downwardly from the partition 37.

The separation of the emulsion components is completed within the washing chamber C, and the clean oil passes upwardly within said chamber to the space above the upper hay section partition 36, while the removed water flows to the lower portion of the chamber. Any gas which may have been separated rises to the space beneath the partition 19 and upwardly through a gas riser 40 into the upper portion of the turbulence chamber B to be disposed of along with the gas separated in the latter chamber. A

clean oil outlet 41 conducts oil from the upper portion of the washing chamber C, the positioning of said outlet a short distance below the partition 19 serving to maintain a predetermined oil level within the chamber. The removed salt water is taken off from the bottom of the washing chamber through an outlet 42 and a conventional water leg 43 which has its upper end vented to the turbulence chamber B by a gas pipe 44. The latter structure is usual and customary, and serves to maintain a suitable body of washing water within the lower portion of the chamber C. Obviously, the water leg 43 may be varied to shift the level within the washing chamber, but it is normal to maintain the interface between the oil and water layers within the confines of the hay section 34.

The lower partition 15 serves as a heat-exchanging surface and transmits units of heat from the relatively high temperature heating chamber A into the lower section of the body of washing water present within the washing chamber C. The emulsion stream flowing downwardly through the flume 33 is first introduced into the chamber C by being directed into this heated lower portion of the body of washing water. Any heat the emulsion stream may have lost in its passage through the upper portion of the treater is thus restored, and the breaking of the emulsion is completed in an efficient fashion. By reason of the lower partition 37, the thermosyphonic or convection flow of the washing water immediately above the partition 15 is limited to the space between said partition and the former partition 37. Thus, as the emulsion stream and its components pass upwardly through the washing section, they incur increasingly cooler zones whereby the clean oil, which eventually reaches the portion of the washing chamber above the upper partition 39 is at a temperature at which it may economically be conducted to storage. Of course, if it is so desired, the conventional type of heat exchanger may be incorporated into the oil discharge line so as to cool said oil by means of the incoming emulsion stream and in addition conserve this heat content by pre-heating of the emulsion stream. However, such a structure would only be employed for reasons of economy since this method and means, by initially heating the emulsion stream before any treatment steps are employed, assures full and complete separation of the emulsion into its various components.

The flume 20 also aids to some extent in maintaining a temperature of the washing water within the chamber C, but it is pointed out that the emulsion stream in flowing upwardly through the flume does not heat the body of clean oil at the upper end of the chamber C to an extent sufficient to cause undesirable results.

In Figs. 4, 5 and 6 is illustrated a modification of this method and structure which is substantially identical in many respects to that previously described. The principal difference resides in the structure of the downwardly directed flume 33 which, in the modification, is replaced by a relatively large diameter pipe 45 extending axially of the treater tank and within which the upwardly directed flume 20 is concentrically disposed. The upper end of the pipe 45 is connected into a relatively large opening 46 cut in the center of the upper partition 47 which otherwise is identical in all respects to the upper partition 19 previously described. In all other respects, this modified form of the invention is substantially

identical to the first form, and the same numerals have been utilized to designate the various elements.

The lower end of the pipe 45 terminates a short distance above the lower partition 15 and carries a radially outwardly directed flange 48 which serves as a baffle and causes the downwardly flowing emulsion stream to spread out over the upper surface of the hot partition 15 before passing upwardly into the hay section 34. This second form of the invention differs in operation from the first form principally in that heat dissipated from the flume 20 is absorbed directly by the downwardly directed emulsion stream flowing from the chamber B, rather than being transferred to the body of liquid within the washing chamber C. The provision of the flange 48 also prolongs the flow of the emulsion stream in the vicinity of the relatively hot partition 15 which forms the upper end of the heating chamber A, the two heat exchange functions recited serving to further maintain the temperature of the emulsion stream prior to its final washing step. In all other respects, the operation of said modification may be considered as substantially identical to that previously recited.

It is to be pointed out that in all the forms of the invention illustrated, the large central flume extending upwardly from a point immediately above the heater tube provides an additional advantage in the warming up of these treaters. It is sometimes necessary to shut a treater down for various reasons, and in cases where heavy oil is being handled, such oil has a tendency to congeal, and considerable time is required to bring the treater back up to an operating temperature because the oil is viscous and resists convection flow. In the case of the present invention, the central flume is filled with water which will quickly accept heat from the heater tube and thus act as an elongate central heating element which will accelerate the warming up of the entire treater and greatly speed its return to an operating temperature.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. The method of treating oil well emulsions which includes, first passing the emulsion stream through an initial heated washing zone containing a body of heated water the emulsion stream being passed in contact with said water, and therein heating the emulsion to its highest temperature, then elevating the emulsion in a segregated path through bodies of water and oil into a segregated zone and therein releasing gas, then carrying the emulsion downwardly through a degassing zone above all water zones without added heat and thoroughly agitating the emulsion back and forth to remove gas, then conducting the emulsion in a segregated path downwardly through a second body of water of lower temperature than the washing zone and having no connection with said zone and discharging said emulsion into said second body of water and therein separating water from the emulsion, then conducting oil upwardly through said second body of water, releasing water from said second body of water, and then carrying off the oil.

2. An oil well emulsion treater including, an

upright tank having a heating and washing chamber at its bottom, a heating element in the heating chamber, an exterior emulsion inlet to the heating chamber, a turbulence chamber at the top of the tank, a washing chamber in the tank between the heating and turbulence chambers adapted to hold liquids and sealed off from the heating and washing chambers, a conductor leading continuously from the heating chamber through the washing chamber to an elevated point in the turbulence chamber, a gas outlet from the turbulence chamber, a second conductor leading from the turbulence chamber to the washing chamber, an oil outlet from the washing chamber, and a water outlet from the washing chamber.

3. An emulsion treater as set forth in claim 2, wherein the conductors extend concentrically in heat exchange relation with one another.

4. An oil well emulsion treater including, a tank having a gas outlet at its top, a heating chamber at the bottom of the tank, a heating element in the heating chamber, an emulsion inlet to the heating chamber immersed in liquid in said chamber, a turbulence chamber at the top of the tank having a gas space, a washing chamber in the tank between the heating and turbulence chambers sealed off from said chambers, an influent conductor separate from the emulsion inlet leading from the heating chamber through the washing chamber to an elevation in the turbulence chamber, a second conductor leading from the turbulence chamber to the bottom of the washing chamber, a water outlet leading from the lower end of the washing chamber above the heating chamber connected with the gas space of the turbulence chamber, an oil outlet leading from the washing chamber below the bottom of the turbulence chamber, and baffles in the turbulence chamber below the upper end of the influent conductor.

5. An emulsion treater as set forth in claim 4, wherein the second conductor surrounds and is spaced from the influent conductor and leads from an opening in the bottom of the turbulence chamber.

6. An emulsion treater as set forth in claim 4, wherein the baffles below the upper end of the influent conductor extend across the tank, one having its edges spaced from the annular wall of the tank and another below extending from the tank walls inwardly and having a central opening surrounding the influent flume.

7. An emulsion treater as set forth in claim 4, with a filter medium in the washing chamber through which the conductors extend.

8. An oil well emulsion treater including, an upright tank closed at its top and bottom and having a gas outlet at its top, a lower partition across the tank sealing off a heating chamber at the bottom of the tank having an influent inlet, an upper partition across the tank forming a turbulence chamber thereabove having a gas space at the top of the tank, a washing chamber in the medial portion of the tank between the lower partition and the upper partition sealed off from the heating chamber, a down pipe from the turbulence chamber to the bottom portion of the washing chamber, the heating chamber being adapted to be filled with a body of water, a flume extending from the heating chamber through the washing chamber and into the turbulence chamber for conducting emulsion from the heating chamber through the washing chamber to the turbulence chamber and sealed off

from the washing chamber, a water outlet from the lower portion of the washing chamber, an oil outlet from the upper portion of the washing chamber, and a heater in the heating chamber.

9. An oil well emulsion treater as set forth in claim 8, wherein the sole source of heat is in the heating chamber.

10. An oil well emulsion treater as set forth in claim 8, with baffling elements in the turbulence chamber between the outlet of the flume and the inlet to the down pipe.

11. The method of treating oil well emulsions which includes, first passing the emulsion stream through an initial heated washing zone containing a body of heated water the emulsion stream being passed in contact with said water, and therein heating the emulsion to its highest temperature, then elevating the emulsion in a segregated path through bodies of water and oil into a segregated zone and therein releasing gas, then carrying the emulsion downwardly through a degassing zone above all water zones without added heat and thoroughly agitating the emulsion back and forth to remove gas by repeatedly spreading the emulsion stream in substantially horizontal layers, then conducting the emulsion in a segregated path downwardly through a second

body of water of lower temperature than the washing zone and having no connection with said zone and discharging said emulsion into said second body of water and therein separating water from the emulsion, then conducting oil upwardly through said second body of water, releasing water from said second body of water, and then carrying off the oil.

12. An emulsion treater as set forth in claim 4, 10 wherein the baffles below the upper end of the influent conductor extend horizontally across the tank, one having its edges spaced from the annular wall of the tank and one having a central opening surrounding the influent flume.
